UNITED STATES PATENT OFFICE.

LORENZO D. DARROW, OF NORTH PLAINFIELD, NEW JERSEY.

ENSILAGE PACKER.

Application filed November 5, 1921. Serial No. 513,064.

To all whom it may concern:

Be it known that I, LORENZO D. DARROW, a citizen of the United States of America, residing at North Plainfield, in the county 5 of Somerset and State of New Jersey, have invented new and useful Improvements in Ensilage Packers, of which the following is a specification.

This invention relates to improvements 10 in ensilage packers, and the principal object is to produce a device of this nature which may be caused to automatically turn upon being raised and lowered so as to pack all portions of the ensilage into the silo with 15 equal firmness.

Another object is to produce a device of 20 this nature which shall be simple of construction, cheap to manufacture, and highly efficient for the purpose for which it is de- 25 signed.

With these and other objects in view, which 30 will be more apparent as the specification proceeds, the invention resides in certain novel construction and combination and arrangement of parts, the essential features of 35 which are hereinafter fully described, are particularly pointed out in the appended claims, and are illustrated in the accompanying drawing, in which:—

Figure 1 is a top plan view of my improved ensilage packer.

Figure 2 is a vertical sectional view of the same.

Figure 3 is a detail sectional view on the 35 line 3—3 of Figure 2.

Figure 4 is a view similar to Figure 3 taken on the line 4—4 of Figure 2.

Like characters of reference refer to like parts in both views.

Referring to the drawing in detail, 40 represents a base portion which may be of any suitable size or shape suitable for the purpose, and is preferably formed with a well 11 in which certain working parts, 45 hereinafter described, are suspended. Secured to the base 10 in any desirable manner are a plurality of radially arranged tamping bars or blades 12 which may be of any suitable length, structure and material, and 50 are arranged so as to balance each other.

An upper body section 13 is provided with a central aperture 14 and with a gear surface 15 surrounding said aperture. The under 55 face of member 13 is provided with a plurality of spring pressed click-pawls 16 which engage a ratchet wheel 17, said pawls and

ratchet wheel being housed in said well 11. Members 10 and 13 may be secured together in any suitable manner, as by bolts.

The ratchet wheel 17 is secured to a disk 60 18 which projects up into an aperture 14 and is formed with a pair of upstanding lugs 19 which form bearings for a rotatable shaft 20 which carries at one end a gear wheel 21 meshing with the gear surface 15. Rigidly 65 secured to shaft 20 between the lugs 19, are two ratchet wheels 22 which are arranged on opposite sides of a pulley 23 carrying ratchet pawls 24 engaging wheels 22. A rope 25 passes about pulley 23 having one end secured to a stationary member and the other end operable by any suitable to-and-fro member (not shown) for raising and lowering the entire device to effect tamping.

In operation, as the device is drawn up, 75 the pulley 23 is turned causing pawls 24 to turn the wheels 22, shaft 20 and gear 21. Gear 21 meshing gear 15 turns the body sections and tamping bars a portion of a turn. Upon the release of the rope the entire device descends, but the ratchets 16 and 80 wheel 17 prevent return movement of all parts except the pulley which ratchets idly back.

While I have described what I deem to be 85 the most desirable embodiment of my invention, it is obvious that many of the details may be varied without in any way departing from the spirit of my invention, and I therefore do not limit myself to the exact 90 details of construction herein set forth nor to anything less than the whole of my invention limited only by the appended claims.

What is claimed as new is:

1. A device of the class described, the 95 combination of a body portion formed with gear teeth, a gear co-operative with said teeth, a pulley, and means between said gear and pulley.

2. A device of the class described comprising a tamping mechanism, a pulley, and means operable by said pulley for rotating 100 said tamping mechanism.

3. A device of the class described, comprising a rotatable tamping body, a member rotatably mounted in said body, means between said body and said member for permitting rotation of said member in one direction, a pulley mounted on said member, and means between said pulley and said 110 body for rotating the device in one direction.

4. A device of the class described, com-

prising a rotatable tamping body, a member rotatably mounted in said body, a ratchet carried by the lower end of said member, a shaft rotatably supported on the upper portion of said member, and a gear on said shaft and co-operative with said body as and for the purpose set forth.

5. A device of the class described, comprising a rotatable tamping body, a member rotatably mounted in said body, a ratch-

et carried by the lower end of said member, a shaft rotatably supported on the upper portion of said member, a pulley loose on said shaft, means whereby said pulley may operate said shaft, and means whereby said shaft may operate said body. 15

In testimony whereof I have affixed my signature.

LORENZO D. DARROW.
